GASEOUS FUEL MIXING DEVICE

Filed Feb. 3, 1941

INVENTOR:
FRANK G. SZAGER
By *Martin P. Smith*, ATTY.

1. A device for mixing gaseous fuel and air, comprising a housing having a central mixing chamber, a pair of fan-like impellers mounted within said chamber, and a pair of bearing rings secured to the upper and lower ends of the housing, each bearing ring having a central threaded aperture, a screw being seated in each aperture, and a lock nut being secured to the outer face of each screw.

UNITED STATES PATENT OFFICE

2,325,285

GASEOUS FUEL MIXING DEVICE

Frank G. Szager, Los Angeles, Calif.

Application February 3, 1941, Serial No. 377,167

1 Claim. (Cl. 48—180)

My invention relates to gaseous fuel mixing devices, particularly of the type that are utilized in connection with internal combustion engines, and the principal objects of my invention are, to generally improve upon and simplify the construction of the existing forms of gaseous fuel mixing devices, to provide a mixing device of unitary construction that may be readily installed in the fuel line between a carburetor and the intake manifold of the engine, or said device being built into and forming a part of the carburetor on the gaseous fuel outlet side thereof and further, to provide a relatively simple, practical, and inexpensive gaseous fuel mixing device that will perform the functions of a supercharger in the delivery of a dry, thoroughly mixed gaseous fuel to the combustion chambers of the engine with which the mixing device is associated.

Further objects of my invention are, to provide a gaseous fuel mixing device having a pair of cooperating fan-like impellers that are rotated by the suction through the carburetor and intake manifold so as to produce a high degree of turbulence within the mixing chambers in which said impellers operate, with the result that an extremely thorough and intimate mixture of air and liquid hydrocarbon is produced, which mixture is comparatively dry, due to the breaking up of the heavy particles of liquid hydrocarbon, and the drier mixture thus obtained produces materially increased effective results when ignited in the combustion chambers of the engine.

With the foregoing and other objects in view, my invention consists in certain novel features of construction and arrangement of parts that will be hereinafter more fully described and claimed and illustrated in the accompanying drawing in which:

Fig. 1 is a vertical section taken through the center of a gaseous fuel mixing device constructed in accordance with my invention.

Fig. 2 is an elevational detail view taken looking in the direction indicated by the arrow 2 in Fig. 1.

Fig. 3 is a horizontal section taken on the line 3—3 of Fig. 1.

Fig. 4 is a top plan view of one of the impellers removed from the mixing chamber of the device.

Fig. 5 is a perspective view of one of the bearings for the impellers.

Referring by numerals to the accompanying drawing which illustrates a preferred embodiment of my invention, 10 designates a part of a carburetor or a duct leading therefrom and 11 designates a portion of the intake manifold of an

internal combustion engine. Interposed between the parts 10 and 11 is a housing 12 formed in two parts that are practically identical in size, form, and construction, and said parts being detachably secured to each other by means of fastening devices 13, such as screws or bolts, that pass through flanges on the adjacent edges of the parts of the housing. Suitable packing is arranged in the joints between the parts of the housing 12 and between the ends of said housing and the parts 10 and 11.

The chamber 14 within housing 12 contains the fan-like impellers and therefore functions as a mixing chamber and the open opposite ends of this chamber communicate respectively with the passage ways through the ducts 10 and 11.

To provide bearings for the impellers, rings 15 are formed integral with the upper end of the upper part of the housing and with the lower end 20 of the lower part, and these rings project into and are permanently secured by welding or otherwise to flanges 16 that are detachably connected by bolts or otherwise to corresponding flanges on the carburetor 10 and intake manifold 11.

Extending diametrically across each ring 15 and formed integral therewith is a narrow bar 16, in the center of which is formed a threaded aperture 17. Screw seated in each aperture is a screw 18 of hardened metal, the inner end thereof being pointed as designed by 19, and seated on said screw and bearing against the outer face of the bar 16 is a nut 20 that functions as a lock nut to secure the screw in its adjusted position.

At diametrically opposite points on the parts 35 forming the housing 12, the flanges that receive the screws 18 are spread apart as designated by 21 a sufficient distance to accommodate the ends of a bar 22 that extends diametrically across the mixing chamber 14. Parts of the packing used 40 between the flanges of the housing members 12 surround the ends of the bar 22 that are positioned between said flanges and certain of the screws 18 pass through the ends of the bar 22 to rigidly secure the same to the housing.

Formed on the upper and lower faces of the central portion of bar 22 in axial alignment with the screws 18 are cup bearings 23.

The fan-like impellers that are mounted for operation in chamber 14 within housing 12 are practically identical in size, form, and construction, and one of said impellers is shown in plan in Fig. 4. This impeller comprises a peripheral ring 24, preferably wire, and secured thereto are the ends of a diametrically arranged narrow bar 25. Formed integral with the center of this bar

25 is a short pointed pin or lug 26 that is adapted to engage in one of the cup bearings 23 on cross bar 22.

The intermediate portion of a narrow strip of metal or wire 27 is spaced apart and occupies a plane parallel with the ring 24 and the end portions of this bar or wire are curved toward and fastened by welding or otherwise to the ring 24 at diametrically opposite points. The central portion of this bar 27 is widened to form a disc 28 and formed in the outer face of said disc is a shallow recess 29 which may be conical in shape and which provides a bearing for the end of the corresponding screw 18.

The parts just described comprise a substantially one-piece skeleton impeller frame and one frame is positioned above the cross bar 22 and the other frame is positioned below said cross bar. The impeller frames thus arranged are mounted for independent rotation between the screws 18 and the bearings 23 on the upper and under sides of cross bar 22.

Arranged between the ring 24 and bar 27 of each impeller frame is a series of radially disposed blades or vanes 30 that are correspondingly inclined vertically, thus forming in effect a bladed fan and the blades of the upper one of the impeller frames are oppositely inclined with respect to the blades carried by the lower frame. The outer ends of the blades 30 are rigidly secured by welding or otherwise to the peripheral rings 24 and the cross bars 25 of the impeller frames.

In operation, the impellers are rotated as a result of the flow of the gaseous fuel from the carburetor to the intake manifold, which flow is induced by the suction produced in the combustion chambers of the engine on the suction strokes of the pistons therein, and as the blades of the two impellers are oppositely arranged with respect to each other, said impellers will simultaneously rotate in opposite directions.

Obviously, this rotation of the impellers in opposite directions produces a marked degree of turbulence in the chamber 14 and a consequent breaking up of the larger particles of liquid hydrocarbon so that the gaseous fuel in a thoroughly mixed and comparatively dry condition is delivered to the intake manifold which leads to the engine cylinders.

This thorough mixing of the air with the liquid hydrocarbon is particularly effective while the engine is operating at higher speeds and under such conditions the mixing device performs the functions of a supercharger so as to bring about increased efficiency of engine operation.

Inasmuch as the impellers rotate in opposite directions, the flow of air and liquid hydrocarbon into the mixing chamber is equalized so that the flow of the gaseous mixture from the device to the intake manifold is made much more uniform than if a single impeller or fan were used, and there is an entire absence of tendency of the incoming air and liquid hydrocarbon to stratify in the

mixing chamber or in the intake manifold through which said mixture passes.

It is to be noted that the skeleton impellers utilized in my improved structure are entirely devoid of hubs and axles and that small square openings are formed between the inner ends of the blades, which provision, according to repeated tests and experiments, materially increases the utility and efficiency of the device, inasmuch as there is no restriction or baffling of the flow of gaseous fuel through the axes of the impellers. Further, the cross bars 25 and 27, which are subject to very little strain, may be made very narrow and bearings 23 and discs 28 may be made very small in diameter thus offering minimum restriction to the flow of gaseous fuel through the device.

Thus, any minute drops of gasoline in the vapor passing through the impellers will be broken into finer spray to assist in more complete vaporization of the fuel before the same enters the combustion chambers of the engine.

Thus it will be seen that I have provided a gaseous fuel mixing device that is relatively simple in construction, inexpensive of manufacture, and very effective in performing the functions for which it is intended.

It will be understood that minor changes in the size, form and construction of the various parts of my improved gaseous fuel mixing device may be made and substituted for those herein shown and described, without departing from the spirit of my invention, the scope of which is set forth in the appended claim.

35 I claim as my invention:

In a gaseous fuel mixing device, the combination with a two part housing providing a mixing chamber, said housing comprising a pair of ring flanges, and housing members having their inner ends detachably connected, the outer ends of said housing members being provided with openings and rigidly seated in said ring flanges, diametrically arranged narrow bars disposed across the openings at the outer ends of said housing members, bearing members adjustably seated in the centers of said bars, a diametrically arranged bar extending across the center of the mixing chamber in said housing, the ends of which last mentioned bar are clamped between the connected ends of said housing members, upper and lower bearing members formed on the center of said mentioned bar, of impeller frames arranged for independent operation between said bearing members each frame including a peripheral ring, 40 a plurality of radially disposed inclined blades arranged within each impeller frame with the blades for one frame oppositely inclined with respect to the blades of the other frame the outer ends of the impeller blades being secured to said peripheral rings and the inner ends of the blades of each set being spaced apart to provide openings to permit the free flow of gaseous fuel axially through the impellers.

FRANK G. SZAGER.
